L. R. NELSON

LAWN SPRINKLER

Filed June 9, 1924

INVENTOR.

L.R.Nelson,

BY *L. M. Nelson*

ATTORNEY.

UNITED STATES PATENT OFFICE.

LEWEN R. NELSON, OF PEORIA, ILLINOIS.

LAWN SPRINKLER.

Application filed June 9, 1924. Serial No. 718,720.

To all whom it may concern:

Be it known that I, LEWEN R. NELSON, a citizen of the United States, residing at Peoria, in the county of Peoria and State 5 of Illinois, have invented new and useful Improvements in Lawn Sprinklers; and I do hereby declare that the following is a full, clear, and exact description of the invention which will enable others skilled in 10 the art to which it appertains to make and use the same.

This invention pertains to lawn sprinklers particularly of the drawn metal type.

An object of the invention is to produce 15 a sprinkler of a new form that can be drawn up from sheet metal.

Another object is to furnish a simple form 20 of sprinkler-head made up of but two main parts one of which is provided with perforations by which to discharge water streams over a complete semi-circular area and arranged so that said sprinkler-head may be changed to new locations without first requiring the water to be shut off, that the nut 25 or fitting for the attachment of the hose may be housed in the head out of harm's way, and that can be drawn up from sheet metal in one piece, whose walls may be attached to the other portion or bottom.

30 Another object is that of producing the body of a lawn sprinkler of a substantially flat semi-circular type whose sides and top are drawn from a single piece of metal by means of dies, one of the walls of said body, 35 termed its front, having a semi-circular form at a low level, the other or rear wall being straight but raised higher than the said front wall to admit into it the customary nut for receiving any usual hose fitting.

40 A further object is to produce a sprinkler-body of a relatively squat form substantially semi-circular, and one that when filled with water when in use will not tilt due to strains imposed by the hose connected with it.

45 Still another object is to provide an extremely rigid and strong sprinkler body of drawn metal of a substantially low flat type semi-circular in form by forming in its top a series of concentric concave and convex 50 surfaces and providing for said body an attached inwardly concave bottom which, while resisting internal water pressure, also permits the sprinkler to lie steadily upon uneven surfaces when in use.

55 In the appended drawing forming part hereof,

Figure 1 shows my new lawn sprinkler in perspective as seen from the rear.

Figure 2 is a plan of the sprinkler shown on a larger scale. 60

Figure 3 is a transverse sectional elevation of the same taken on line 3—3, Figure 2.

Figure 4 is a rear elevation of the sprinkler, and

Figure 5 shows the under side of the 65 sprinkler produced on a much smaller scale.

The body of the sprinkler is designated as a whole by the character 1, its bottom being denoted at 2. Said body is drawn from sheet metal as the best method of production and 70 comprises what I shall term a front wall denoted at 3 which is of semi-circular outline and relatively low, while its rear wall 4 is straight and relatively higher at the middle portion of its length, the said walls, as 75 shown in the drawing, being substantially perpendicular to the plane of the base of said body. The top of the latter at its highest point is domed as shown at 5, dropping off into the said rear wall and sufficiently high above the base line to admit the threaded nut 6 that receives the fitting of a 80 hose, not shown. The top of the body at the base of the dome lies at a lower level than the latter and said rear wall, and is substantially flat, taking a semi-circular form, as 7, concentric to the dome and body-base, the outer margin terminating in a shoulder 7' 85 which drops away into a concave 8 likewise concentrically placed, outward from which the body falls away into the mentioned low front wall 3, the latter being but little more than one-half the full height of the device including the dome 5.

The metal each side of the dome at the 90 rear side of the body is brought down into the straight integral rear wall 4, the entire structure described providing a very rigid body which cannot be easily changed in form by blows or pressures thereon in use, the 100 whole being thoroughly braced by the succession of concentric ridges and the vertical walls 3, 4.

The free or lower edges of the wall lie in one plane and engage upon the bottom 2 105 described, the marginal edge of the latter and the said edges of the walls being rolled together, Figure 3, to make a thoroughly water-tight joint. The bottom constitutes the closure for the sprinkler and the peculiar form thereof is notable in that it is braced as against internal water pressure 110

by being concaved inwardly or in the direction of such pressure as clearly shown in Figures 3 and 5 and this concave form also permits the sprinkler to lie upon and adapt itself readily to uneven surfaces.

A series of perforations 10 for the discharge of water is formed in the concave surface 8 and such perforations are disposed at such positions in said concave surface that they discharge streams at different angles and thereby a considerable territory can be sprinkled. Again, in the surface 7 are perforations 11 which project streams nearly vertically therefrom. All of the holes in the body are placed in protected areas so that blows that might tend to dent the metal must be received upon the convex braced portions and the holes are not likely to be affected and for that reason the direction of discharge of the streams will be constant.

The holes in the concave surface 8 extend over a complete half circular area, and, in order that this arrangement of holes may be best placed on a surface maintained evenly over the body the latter is extended rearwardly from or beyond the center from which the lines of holes are described. That is to say, the metal of the body in order to accommodate the holes to be thus laid out must have a rearward extension sufficient to accommodate such arrangement before being brought down into the rear wall 4, this being clear from a study of Figure 2, for example, the dotted line parallel to the rear wall where it crosses the line 3—3 being the center from which the lines of holes are struck. This extension provides a considerable space, also, for the introduction of the nut 6 while keeping a straight rear bracing wall and without complicating the forms of dies, and altogether providing a very simple construction.

The sprinkler body is believed to be new since it is of extended semi-circular form and substantially flat and kept as low as possible at its forward or front wall, but gradually rising into the concave and convex surfaces to the full height of the dome 5, which latter is just high enough to take beneath it the mentioned nut 6.

I have found that a sprinkler-body in order to best maintain a level position and

one that cannot be easily rocked upon the ground by twisting action of the hose under pressure of water, must be fairly heavy but at the same time must be made of metal of light weight in order that the cost of manufacture may be kept as low as possible. The necessary weight is obtained in the semi-circular type of sprinkler herein by making the body with a top and bottom of the full area of the ground surface on which the body lies so that as large a bulk of water as possible can be employed to hold the sprinkler firmly upon said ground surface, rather than to make said body of the open center type shown in my prior Patent No. 1,202,208 issued Oct. 24, 1916, and thus secure stability. Added to this is the described portion of the body that lies rearward of the center about which the lines of perforations 10 are arranged which gives further and considerable weight of water for stabilizing purposes.

I claim:

A lawn sprinkler comprising a base of substantially semicircular form having a marginal edge upon the ground, a top of similar contour including an integral side wall and an integral rear straight wall, both being brought down from the said top upon the margin of said bottom and secured thereto, the space within the walls and between said bottom and top being a full receiving space for water, a hose connection secured in the said rear wall at the middle of the length thereof opening into the body-space, said rear wall being reduced in height at each side of the position of said hose connection, the said top of the body being domed at said rear wall and being reduced in height therefrom in all directions in a succession of concentric zones of varying contour, the zone adjacent the said side wall being inwardly and downwardly curved into said wall and having perforations arranged therein concentric to the said dome of the top, the area of the said top and the said bottom together with the said side wall extending a considerable distance rearwardly from the center about which the lines of perforations are arranged.

In testimony whereof I affix my signature.

LEWEN R. NELSON.
